UNITED STATES PATENT OFFICE.

WENDEL HAHN, OF NEW YORK, N. Y.

CLOTHESLINE-PULLEY.

1,373,130.

Specification of Letters Patent. Patented Mar. 29, 1921.

Application filed December 16, 1919. Serial No. 345,248.

To all whom it may concern:

Be it known that I, WENDEL HAHN, a citizen of Hungary, and a resident of New York, in the county of Queens and State 5 of New York, have invented certain new and useful Improvements in Clothesline-Pulleys, of which the following is a specification.

The present invention relates to improvements in clothes-line pulleys, and has for one 10 of its objects to provide a simple, inexpensive and durable device of this character which can be readily fastened to a wall, or other support, and easily detached therefrom, and which is provided with means 15 for moving the clothes-line in either direction so as to facilitate the placing of the clothes thereon or their removal therefrom.

Another object of the invention is to produce a clothes-line holder of the character 20 described which may be manufactured on a commercial scale, or in other words one which is not so difficult to make as to be beyond the reasonable cost of such a contrivance.

With these and other objects in view, which will more fully appear as the nature 25 of the invention is better understood, the same consists in the combination, arrangement and construction of parts hereinafter 30 described, pointed out in the appended claims and illustrated in the accompanying drawings, it being understood that many changes may be made in the size and proportion 35 of the several parts and details of construction within the scope of the appended claims, without departing from the spirit or sacrificing any of the advantages of the invention.

One of the many possible embodiments 40 of the invention is illustrated in the accompanying drawings, in which:—

Figure 1 is a side elevation of a clothes-line, its holder and support; Fig. 2 is a side 45 elevation of the holder proper, on a larger scale; and Fig. 3 is a section taken on line 3—3 of Fig. 2.

In the drawings, the numeral 10 indicates a support, having a pulley 11 secured 50 thereto, upon which is arranged an endless clothes-line 12. The inner end of this clothes-line is in engagement with the holder proper. This holder comprises a bracket

13, attached to a wall or other support 14, for instance a window frame, by means of 55 screw-bolts 15, or otherwise. From this bracket extends sidewise a horizontally disposed spindle 16, on which is rotatably mounted a grooved pulley 17. To this pulley is eccentrically attached a handle 18, 60 to rotate the same. With the bracket 13 are made integral, or there may be attached thereto, two standards 19, extending radially in opposite directions beyond the periphery of the pulley 17. One of these 65 standards projects above the pulley and the other one below the same, they carrying each a grooved sheave 20. These sheaves are spaced from the pulley and serve as guiding means for the line. 70

The bracket 13 is provided in front of the pulley, preferably at a point at right angles to the connecting line between the centers of the sheaves 20, with a sidewardly disposed adjacent the periphery of the pulley, its face 22, juxtaposed to the pulley, being curved to accommodate, with the groove in the pulley 17, the line 12, preventing the same from leaving the said pulley. 80

In applying the device, one end of the clothes-line is drawn under the upper one of the sheaves 20, passed partly around the pulley 17 between the projection 21, drawn over the lower sheave 20 and around the 85 pulley 11, the two ends thereof being then tied together. It will be understood that, when the pulley 17 is rotated, the clothes-line may be moved backward or forward, as desired. The sheaves 20 and the projection 21 properly guide the movement of the line, so that it cannot leave the pulley 17. Inasmuch as the sheaves 20 are disposed at diametrically opposite portions of the pulley 17, as clearly appears from Figs. 90 1 and 2 of the drawings, the line cannot be crossed on the said pulley, so that the latter is always free to turn. 95

What I claim is:—

In a device of the character described, 100 the combination with a bracket, of a grooved pulley rotatably mounted thereon, two standards on said bracket extending in opposite directions beyond the periphery of said pulley, a grooved guide sheave carried by 105 each of said standards adjacent the periph-

ery of said pulley, and a sidewardly extending projection on said bracket disposed adjacent the periphery of said pulley, the face of said projection juxtaposed to the pulley being curved to accommodate with the groove in said pulley a clothes lines, said projection being disposed on said bracket at

a point at right angles to the connecting line between the centers of said two sheaves.

Signed at New York, in the county of 10
New York and State of New York, this
15th day of December, 1919.

WENDEL HAHN.
